UNITED STATES PATENT OFFICE.

SAMUEL B. ELZEY, OF ATLANTA, GEORGIA.

GATE-LATCH.

SPECIFICATION forming part of Letters Patent No. 225,580, dated March 16, 1880.

Application filed January 6, 1880

To all whom it may concern:

Be it known that I, SAMUEL B. ELZEY, of Atlanta, in the county of Fulton and State of Georgia, have invented a new and useful Improvement in Gate-Latches, of which the following is a specification.

Figure 1 is a front elevation of the improvement shown as attached to a post and with the face-plate removed. Fig. 2 is a sectional elevation taken through the line *x x*, Fig. 1, and showing the face-plate in place. Fig. 3 is a perspective view.

Similar letters of reference indicate corresponding parts.

The invention consists in combining a pivoted latch carrying an arm, a sliding bar carrying an arm, and a spindle carrying an arm, so that the gate may be unlatched by turning the spindle, substantially as hereinafter described and claimed.

A represents a gate-post. In the side of the post A toward the gate is formed a recess to receive the case B, which is secured in place by screws or bolts.

In the lower forward part of the case B is pivoted, by a screw or bolt, C, the latch D. The latch is nearly in the form of a bell-crank lever, pivoted at the junction of its arms, of which the upwardly-inclined one, E, rests upon a downwardly-inclined projection of the slide-bar G, while the other arm rests with its outer end upon the case B.

This arrangement brings the lower side of the latch D into an inclined position, so that the latch will be raised, when the gate is swung shut, by a pin attached to the forward end of the gate, and which passes in through a notch in the lower part of the front flange or side of the case B. As soon as the pin attached to the gate has passed the latch D the said latch falls by its own weight, and prevents the pin from passing out until the said latch has been raised.

The bottom flange and the lower part of the rear flange of the case B project, and the lower and forward parts of the latch D have outwardly-projecting flanges formed upon them, to give a wider bearing to the pin attached to the gate.

Upon the upper side of the hub of the latch D is formed an upwardly-inclined arm, E,

which extends along the upper side of a downwardly-inclined arm, F, formed upon the inner edge of the vertical sliding bar G. The bar G slides up and down along the inner side of the rear flange and through a notch in the top flange of the case B.

The upward movement of the sliding bar G is limited by a stop, H, formed upon or attached to the case B, and which enters a notch, I, in the rear edge of the said bar G. The downward movement of the bar G is limited by a stop, J, attached to or formed upon the case B, and against which the lower end of the bar G, or a projection formed upon the said lower end, strikes. The downward movement of the bar G is also limited by an offset, K, formed upon the upper part of the said bar G, and which comes in contact with the top of the case B. The part of the bar G above the offset K is parallel with the lower part of the said bar, and moves up and down in a recess in the post A.

The part of the bar G above the offset K has a short slot or an elongated hole formed through it to receive the arm L, attached to or formed upon the spindle M, which spindle M passes through the post A, and has knobs N or other handles attached to its ends.

With this construction, by turning the spindle M the arm L will raise the bar G, causing the arm F to raise the arm E, which raises the latch D with it and allows the gate to be opened.

O is a bolt which slides up and down along the forward flange of the case B, and is provided with a thumb-piece, P, which projects through a notch in the front flange of the case B. When the bolt O is pushed down, its lower end, or a head formed upon its lower end, engages with a shoulder, Q, formed upon the hub or pivoted end of the latch D, so that the said latch D cannot be raised until the bolt O has been withdrawn from the shoulder Q. Upon the forward side of the upper end of the bolt O is formed a projection, R, which engages with a similar projection, S, upon the inner side of the front flange of the case B, so that the projections R S may fasten the bolt O raised or lowered, according as the projection R is placed above or below the projection S. The bolt O is held against the front flange

of the case B by a spring, T, attached to the case B, and which presses against the inner side of the said bolt O, as shown in Figs. 1 and 3.

5 The upper and middle parts of the improvement are covered by the face-plate U; but the lower part is left uncovered to form a space for the pin attached to the gate to enter and engage with the latch D. The lower part of 10 the face-plate U has a curved slot formed in it to receive the flange of the latch D when the said latch is raised.

Having thus described my invention, I

claim as new and desire to secure by Letters Patent—

15 In a gate-latch, the combination, with the pivoted latch D and its arm E, of the vertical sliding bar G, with its arm F, the spindle M, and arm L, substantially as herein shown and described, whereby the gate may be unlatched by the movement of the spindle M, as set forth.

SAMUEL BELL ELZEY.
